US0D1063538S

(12) **United States Design Patent** (10) **Patent No.:** **US D1,063,538 S**
(45) **Date of Patent:** **** Feb. 25, 2025**

(54) **DRINKWARE**

(71) Applicant: **Disney Enterprises, Inc.**, Burbank, CA (US)

(72) Inventors: **Marthe Hoffmann**, Los Angeles, CA (US); **Kaitlyn Rosette**, Los Angeles, CA (US)

(73) Assignee: **Disney Enterprises, Inc.**, Burbank, CA (US)

(**) Term: **15 Years**

(21) Appl. No.: **29/839,879**

(22) Filed: **May 24, 2022**

Related U.S. Application Data

(62) Division of application No. 29/747,322, filed on Aug. 21, 2020, now Pat. No. Des. 962,704.

(57) **CLAIM**

The ornamental design for a drinkware as shown and described.

DESCRIPTION

FIG. 1 is a top perspective view of a drinkware showing our new design;

FIG. 2 is another top perspective view thereof;

FIG. 3 is a bottom perspective view thereof;

FIG. 4 is a front elevational view thereof;

FIG. 5 is a rear elevational view thereof;

FIG. 6 is a right side elevational view thereof;

FIG. 7 is a left side elevational view thereof;

FIG. 8 is a top plan view thereof;

FIG. 9 is a bottom plan view thereof;

FIG. 10 is a top perspective view in a second position thereof; and,

FIG. 11 is another top perspective view in the second position thereof.

The portions of the drinkware shown in broken lines form no part of the claimed design.

The stippled portions of the drinkware indicates a contrast in appearance.

1 Claim, 10 Drawing Sheets
